CLARENCE J. COBERLY, OF LOS ANGELES, CALIFORNIA, ASSIGNOR TO KOBE, INC., OF HUNTINGTON PARK, CALIFORNIA, A CORPORATION OF CALIFORNIA

TORCH TIP WITH DEFLECTORS

Application filed April 15, 1930. Serial No. 444,492.

My invention relates to the art of cutting metals by the use of a gas jet such as a jet of oxygen, and relates particularly to a torch tip having means therewith for producing a diverging jet of cutting gas which may be used to cut diverging slots in metal plates or the walls of pipe.

My invention is of special utility in cutting slots in pipe so as to make well screen or strainers therefrom. It is desirable that these slots in the pipe walls diverge inwardly so as to provide a clearance which will permit free inward passage of sand or other particles of substance of a size to pass the entrance of the slot. Accordingly, it is an object of this invention to provide a torch tip having means therewith for causing the cutting jet to diverge, thereby making it possible to employ such jet to cut a diverging slot desirable in screens which are to be used in wells for the purpose of holding back sand, earth and gravel formations.

It is an object of the invention to provide a cutting torch with an external deflector which will operate on the issuing jet of cutting gas in a manner to cause divergence of such jet.

A further object of the invention is to provide a simple cutting tip construction having the valuable utility and the novel features hereinabove indicated.

Further objects and advantages of the invention will be made evident throughout the following part of the specification.

Referring to the drawing which is for illustrative purposes only,—

Fig. 1 is an enlarged vertical cross section through a cutting tip embodying my invention.

Fig. 2 is a bottom plan view corresponding to Fig. 1.

Fig. 3 is a cross section of a deflector member of the character shown in Fig. 1, but having the deflector surface thereof set at a greater angle.

Fig. 4 is a fragmentary section of a plane represented by the line 4—4 of Fig. 1, showing the lower end of the cutting tip, the diverging jet produced thereby and a metal wall cut by such jet.

Fig. 5 is an enlarged fragmentary vertical section of the lower end of a cutting tip embodying an alternative form in which the invention may be practiced.

Fig. 6 is a fragmentary cross section similar to Fig. 5 showing another configuration of the deflector member.

Fig. 7 is a bottom plan view similar to Fig. 2, but showing an alternative form of replaceable or interchangeable deflector member.

The embodiment of my invention as shown in Fig. 1 consists of a cutting torch tip 11 consisting of a metal body 12 of the general form used in welding and cutting torch tips. 65 This body 12 has a central passage 13 for a cutting gas, which in general practice is relatively pure oxygen, and a plurality of outer gas passages 14 through which an oxygen and acetylene mixture is delivered 70 for the purpose of feeding heating flames 19 which issue from the lower end of the cutting tip 11 in the customary manner indicated in Fig. 4. The extreme lower end of the central or oxygen passage 13 is counter- 75 bored at 15 to receive an outlet bushing 16 having an axially extending opening or jet passage 17 therein, the size of which opening determines the diameter of the jets of oxygen delivered by the torch tip 11. The 80 tip 11 includes a deflector member 18 so formed as to provide a deflector surface 20. This deflector surface 20 is formed on the end of a radial bar 21 which projects inwardly over the lower face of the tip 11 from a 85 ring 22 replaceably secured on the cylindrical lower extremity 23 of the body 12, means, such as a set screw 24, being provided to secure the ring 23 against inadvertent removal.

In the form of the invention shown in Figs. 90 1 to 4, the deflector represented essentially by the deflector surface 20 is situated at one side of the mouth of the jet passage 17 and is downwardly and inwardly sloped in substantially the manner shown so that the lower 95 portion of the surface 20 will project into the path of the issuing jet of oxygen, causing the issuing jet of oxygen to diverge in the manner of the jet 25 shown in Fig. 4. The deflector causes the jet to flare or diverge in 100

a plane parallel to a horizontal line drawn across the deflector surface 20, or in other words, the jet is flared laterally in the general direction indicated by the deflector surface 20. When a diverging jet, such as indicated at 25 is employed in the customary manner to cut a slot in a body of metal 26, which may be the wall of a pipe or the plate of a filter or strainer, a slot 27 will be formed having side walls 28 which diverge downwardly.

In Fig. 3 I show a deflector member 18 of the same character as the deflector 18 of Fig. 1, but with the deflector surface 20 thereof coinciding with a line B—B disposed at a greater angle from the axis of the cutting tip than the line A—A, which represents the slope of the deflector surface 20 of Fig. 1. This increased slope of the deflector surface, as indicated in Fig. 3, causes greater divergence of the oxygen jet so as to produce greater divergence of the side walls defining a slot cut thereby. Deflector members 18 may be made with the deflector surfaces 20 thereof at various angles enabling the selection of a deflector member suited to the character of slot which is to be cut, it being remembered that the various deflector members 18 are interchangeable.

In the form of the invention shown in Fig. 5, a deflector member 30 is formed integrally with the removable bushing 31 of a cutting tip 32 having a central oxygen passage 33 and outer passages 34. The bushing 31 is provided with an axial gas passage 35, which extends from the upper end of the bushing to a flat face 36 near the lower end of the bushing. The deflector member 30 consists of a side portion of the bushing 31 which projects downwardly beyond the face 36 and is equipped with a deflector surface 37. The bushing 31 may be conveniently made in the following manner.

A cylindrical bar of metal is first drilled inwardly from the end 38 thereof to a stopping point indicated by dotted lines 40, this stopping point being substantially coincident with the face 36. The face 36 and the deflector surface 37 are then simultaneously formed by milling out that portion of the lower end of the sleeve indicated by dotted lines 41 and 42 and by the faces 36 and 37. When this body of metal is removed, the lower end of the oxygen passage 35 is opened up so that a flow of oxygen may pass freely therethrough to be deflected by the deflector surface 37 which projects slightly into the path of the issuing jet of oxygen.

In Fig. 6, I show a bushing 45 having a deflector face 46 substantially parallel to the axis of the oxygen passage 47 extending through the bushing 45. The presence of the surface 46 at the side of the oxygen passage 47, although not projecting directly into the path of the issuing jet of oxygen, has the

effect of producing a slight divergence of the jet. Experimental use of the invention indicates that good results may be obtained from the use of a deflector having a flat deflector surface placed so as to operate on the issuing jet of oxygen substantially in the manner shown, but other forms of deflectors may be employed in conjunction with an issuing jet of oxygen with a greater or lesser degree of success.

In Fig. 7, I have shown a deflector member 50 of the general form of the deflector member 18 illustrated in Figs. 1 and 3. This deflector member includes a bar portion 51, which projects radially inwardly from a ring 52 and has the inner end 53 or deflector portion proper thereof pointed and projected over the mouth of an oxygen passage 54, with which a cutting torch body 55 is provided.

From the foregoing, it will be readily perceived that the deflector means employed to engage an issuing jet of oxygen may be made in various forms and may be made integrally or detachable.

Although the simple and preferred form of the invention employs a single deflector plate disposed at one side of the oxygen passage, the invention also comprehends the use of more than one deflector member, such as deflector members placed in diametrically opposite positions, so as to engage opposite sides of the issuing jet of oxygen.

Although I have shown the simple and practical forms of my invention, it is recognized that for the elements shown, other equivalent elements may be employed to accomplish the same results in a substantially identical manner; therefore, the invention is not limited to the details of the foregoing disclosure, but shall be accorded the full scope of the following claims.

I claim as my invention:

1. A cutting torch tip of the character described, comprising a tip body having a cutting gas passage therethrough and a deflector adjacent the mouth of said gas passage for producing divergence of the jet issuing from said gas passage, said body having a plurality of heating gas passages placed in circular arrangement around said cutting gas passage.

2. A cutting torch tip of the character described, comprising a tip body having a gas passage therethrough and a downwardly and inwardly sloping deflector adjacent the mouth of said gas passage for producing divergence of the jet issuing from said gas passage.

3. A cutting torch tip of the character described, comprising a tip body having a cutting gas passage therethrough and means below and adjacent the mouth of said gas passage operating to produce divergence of the jet issuing from said gas passage, said body having a plurality of heating gas passages.

placed in circular arrangement around said cutting gas passage.

4. A cutting torch tip of the character described, comprising a tip body having a gas passage therethrough and a deflector member below the plane of the mouth of said gas passage, said deflector member having a deflector surface sloping downwardly and inwardly relative to the jet issuing from said gas passage and engaging a side of the jet issuing from said gas passage.

5. A cutting torch tip of the character described, comprising a tip body having a cutting gas passage therethrough and a deflector member below the plane of the mouth of said gas passage, said deflector member having a portion projecting into the path of an imaginary cylinder projected from and having the same diameter as said cutting gas passage.

6. A cutting torch tip of the character described, comprising a tip body having a cutting gas passage therethrough and means below and adjacent the mouth of said gas passage operating to produce divergence of the jet issuing from said gas passage, said means having a part disposed at a distance from the axis of said gas passage less than the radius of said gas passage.

7. A cutting torch tip of the character described, comprising a tip body having a gas passage therethrough and a downwardly and inwardly sloping deflector adjacent the mouth of said gas passage for producing divergence of the jet issuing from said gas passage, the lower portion of said deflector being disposed at a distance from the axis of said gas passage less than the radius of said gas passage.

8. A jet diverging means of the character described, for use with a cutting torch tip having a cutting gas orifice, comprising: a body having a face adapted for disposal adjacent the mouth of said cutting gas orifice, said face sloping forwardly and inwardly relative to the axis of said orifice; and means for securing said body to said torch tip.

9. A jet diverging means of the character described, for use with a cutting torch tip having a cutting gas orifice, comprising: a body having a face adapted for disposal adjacent the mouth of said cutting gas orifice, said face sloping forwardly and inwardly relative to the axis of said orifice; and means for securing said body to said torch tip, said means comprising a ring adapted to fit around the end of said torch tip.

10. A jet diverging means of the character described, for use with a cutting torch tip having a cutting gas orifice, comprising: a body having a jet-engaging part; and means for securing said body to said torch tip in such position that said jet-engaging part will be disposed at a distance from the axis of said cutting gas orifice less than the radius of said orifice.

11. A cutting torch of the character described, including: a body having a cutting gas passage therein; and a tubular member set into the forward end of said cutting gas passage, the opening of said tubular member forming a cutting gas orifice, there being a wall projecting forwardly from one side of said tubular member having an inner face sloping forwardly and inwardly in position to engage and produce divergence in a cutting jet issuing from the said orifice.

In testimony whereof, I have hereunto set my hand at Los Angeles, California, this 10th day of April, 1930.

CLARENCE J. COBERLY.
